UNITED STATES PATENT OFFICE

HENRY H. TALBOYS, OF MILWAUKEE, WISCONSIN, ASSIGNOR TO NORDBERG MANUFACTURING COMPANY, OF MILWAUKEE, WISCONSIN, A CORPORATION OF WISCONSIN

TRACK SHIFTER

Application filed October 29, 1927. Serial No. 229,781.

This invention pertains to track shifters and pertains to the type wherein a car is equipped with means for clamping it to the track upon which the car rests and likewise with power actuated means adapted to raise the car and attached track.

More specifically the structure embodies means such as a power actuated spud, a ground bearing shoe or plate attached thereto and two leveling spuds likewise attached to the shoe; suitable braking means being associated with said leveling spuds to control the position of the same and consequently the position of the car and the track when the same are elevated with reference to the road bed or ground through the actuation of the power spud.

A structure embodying the invention is illustrated in the annexed drawings wherein:

20 Figure 1 is an end elevation of the car with the shoe shown as bearing upon the ground or bed and the car and clamped track elevated from the previous position shown in dotted lines,

25 Figure 2 an enlarged detail sectional elevation of the shoe, the various spuds and allied parts,

Figure 3 a horizontal sectional view taken on the line III—III of Figure 2,

30 Figure 4 an enlarged detail sectional view of one of the locking spuds and the clamping or braking means therefor,

Figure 5 a perspective view of one of the braking or clamping elements, and

35 Figure 6 a detail sectional view of the connection between the power spud and the load bearing shoe.

The car may be of any approved type, the body whereof is denoted by 1 and has mounted

40 thereon an engine indicated by 2. Said engine will preferably be of the internal combustion type and is so geared to the axle of a pair of the wheels that it is utilized for driving the car. Clamps as 3 actuated in any

45 suitable manner are adapted to grab the rail 3^a of the track-way and to secure the car unmovably thereto. Inasmuch as these parts are standard and well known they are not shown or described in detail.

50 Extending transversely of the body or

frame of the car is a pair of channel beams or bars 4 and 5 forming tracks for a frame 6 provided with bearings for a shaft 7. Said frame may be locked or held in any desired position on the tracks as has heretofore been done but in the instant case it will be placed in mid position and allowed so to remain.

To one end of the shaft 7 is secured a worm wheel 8 driven by a worm 9 carried by a shaft 10 which may be driven through suitable manually controlled connections (not shown) with the engine 2. Shaft 7 carries a gear 11 which is in mesh with rack-teeth upon the thrust spud or bar 12, said spud being held in proper relation to gear 11 by a suitable guide 13. Said guide is supported by and swiveled upon shaft 7 and may be moved to one or the other side of the vertical through the manipulation of a hand wheel 14 upon the supporting shaft of which is secured a pinion 15 which meshes with a sector rack 16 extending outwardly from bearing 18. Such angular adjusting mechanism is only used however when the spud 12 is alone employed and in the absence of the levelling spuds shortly to be described.

At its lower end spud 12 is pivotally connected, as at 17, to a shoe or bearing member 18 preferably fabricated from a channel bar and plates, as shown, to produce a rugged structure.

The two levelling spuds are denoted generally by 19 and 20 and each is composed of a plurality of flat bars as 21. The lower end of each bar is provided with an elongated slot or opening 22 and a pin 23 passes therethrough and through the upstanding elements of the shoe 18. Said bars are held in spaced relation to each other and the shoe elements by spacing washers 24. Each of the levelling spuds is of like construction as are the parts associated therewith, hence a description of one will suffice for both.

The separate elements 21 extend upwardly and are designed to be clamped in their adjusted positions through the operation of a manually controlled braking mechanism. To this end there is mounted upon the elements 4 and 5 a box-like casting 25 (see more particularly Figures 3 and 4), said casting

having a rectangular opening extending upwardly therethrough (see the right hand end of Figure 3) and overlying the upper end thereof is a plate-like member 26 having upwardly extending elements 27 which form the support for pins 28 and 29 upon which rollers 30 and 31, respectively, are mounted. A second pair of rollers 30^a and 31^a (Figure 2) is mounted at the lower end of the casting and together with the upper rollers serve to guide the members 21 in their up and down movement. Said member 26 is positioned upon the upper end of the box-like member 25 by pins 32 and the parts are held in place by a series of hook bolts 33, the lower end of which underlie bars 34 interposed between the hooked ends and the upper inwardly extending flanges of the rail members 4 and 5. When the nuts 35 are screwed down, the parts are securely locked in place and held against movement with reference to the cross rails 4 and 5.

Interposed between the various elements 21, the rear wall 36 of the box-like member and the forward adjustable compression plate 37 is a series of friction plates. Said plates will preferably be formed of metal elements 39 having secured on opposite sides thereof friction sheet material 40. Said sheet material 40 is somewhat narrower than the width 30 of the plate 39 but slightly greater than the width of the elements 21. The lower ends of said members 39 rest upon a wear plate 41 located in the lower portion of the box, there being a second wear plate 42 located beneath the plate 41. A wear plate 43 is located at the upper end of the box and overlies the pressure producing plate 37, said plate also resting at its lower end upon the wear plate 41. Secured in an opening formed in the wall 44 of the box-like member 25 is a screw threaded bushing 45 in which is mounted a quick pitch screw 46 the inner end of which takes against the bearing block 47 mounted in a recess formed in the adjacent face of the pressure element 37.

A hand lever 48 is attached to the outer end of the screw 46 and by manipulating the handle, pressure may be exerted upon the plate 37 and through it upon the various elements 21 and the interposed friction braking plates. Reverse movement of the handle, of course, relieves the pressure and allows the levelling spud or the elements 21 thereof to pass freely through the friction plates either in an upward or downward direction, as the case may be.

A stop arm 49 is secured in place beneath one of the bolts 35 to limit the outward movement of the lever 48 or when the lever is in that position where the parts are freed of frictional contact.

In operation the car is run along the rails to a point where it is desired to elevate the track. Clamps 3 are then brought into locking relation or engagement with the rails.

The shoe 18 is, of course, at such times in its elevated position but when the car has been secured to the rails the center spud 12 is lowered and the levelling spuds are allowed to pass freely in a downward direction, the levers 48 being at such times thrown outwardly to the release position.

When the shoe 18 has been positioned power may be applied through the shaft 7 to the spud 12 which will cause the car to be moved upwardly carrying with it the rails and the attached ties.

When the track has been brought to the desired elevation, power will be cut off from the driving mechanism and the levers 48 thrown inwardly to the locked position, it being understood, of course, and as will be apparent upon inspection of Figure 3, that the screws 46 are reversed or one is right handed and the other is left handed.

If it be desired to raise one side of the track higher than the other the operator may lock or set the brake of one of the levelling spuds whereby further movement of that spud with reference to the box through which it passes will be inhibited and as a consequence the car and track will be tilted, such tilting action being permitted by the slotted connection at the lower end or ends of each of the levelling spuds and further by the fact that the guide 95 13 for the center spud may turn about the axis of the shaft 7.

When the desired elevation is had either in parallelism to the road bed or at an angle thereto, the operator may maintain such position by manipulating the handles 48 to lock the braking mechanism and at the same time will release the power connection which is operative in relation to the spud 12.

It is to be noted that the levelling spuds take the strain in compression; that they are rugged and will carry a considerable load, consequently they are advantageous over a structure wherein cables are employed to prevent tilting of the car with reference to the center spud or boom.

What is claimed is:

1. The combination with a railway car adapted to be attached to the supporting rails and provided with an independent support adapted to be engaged to raise the car and rails; of means, comprising rigid elements, severally connecting opposite end portions of said support with the sides of the car; and means acting directly upon said rigid elements for severally stopping or retarding the movement of said rigid elements relative to said car while the car is raised on said support.

2. The combination with a railway car adapted to be attached to the supporting rails and provided with an independent support adapted to be engaged to raise the car and rails; of means, comprising rigid elements, severally connecting opposite end portions of

said support with the sides of the cars; and manually controlled friction brakes acting directly upon said rigid elements for severally stopping or retarding the movement of said rigid elements relative to said car while the car is raised on said support.

3. The combination with a railway car adapted to be clamped to the supporting rails and provided with a shoe and a spud adapted to be engaged to raise the car and rails; of means severally connecting the ends of the shoe with the car; and means, acting directly upon said connecting means, for severally retarding or stopping the movement of said connecting means relative to said car during upward movement of said car on said spud whereby lateral tilting of the car may be limited or prevented.

4. The combination with a railway car adapted to be secured to the supporting rails and provided with thrust means for simultaneously raising the car and rails, of independent means severally connected with opposite ends of said thrust means and slidable with reference to the car; and means for severally retarding or stopping movement of said slidable means.

5. The combination with a railway car adapted to be secured to the supporting rails; of a bearing shoe; a spud pivotally connected at its lower end to the shoe at substantially the mid length of the latter; power means for actuating said spud; a pair of spuds pivotally connected one to each end of the shoe; frictional braking means mounted on the car and through which the last named spuds extend; and means under the control of the operator for rendering said braking means effective upon one or the other or both of said spuds.

6. The combination with a railway car adapted to be secured to the supporting rails; of a bearing shoe; a spud pivotally connected at its lower end to the shoe at substantially the mid length of the latter; power means for actuating said spud; a pair of spuds having a pin and slot connection with the shoe, one at each end thereof; frictional braking means mounted on the car and through which the last named spuds extend; and means under the control of the operator for rendering said braking means effective upon one or the other or both of said spuds.

7. In combination with a railway car; means for clamping the same to the supporting rails upon which the car stands; a bearing shoe; a power actuated spud pivotally connected at its lower end to the central portion of the shoe; guides mounted on the car, one to each side of the power spud; a spud passing downwardly through each guide and pivotally connected at its lower end to the underlying end of the shoe; and manually controlled braking means mounted in each of

said guides and acting to arrest the movement of the spuds passing through the guides.

8. In combination with a railway car; means for clamping the same to the supporting rails upon which the car stands; a bearing shoe; a power actuated spud pivotally connected at its lower end to the central portion of the shoe; guides mounted on the car, one to each side of the power spud; a spud passing downwardly through each guide, 70 said spuds each comprising a series of spaced bars; a pivotal connection between the lower end of each of said spuds and the adjacent end of the shoe; a series of friction plates mounted within each guide and between 75 which the bars of the spud extend; and means to force the bars and plates into locking relation.

9. In combination with a railway car; means for clamping the same to the supporting rails upon which the car stands; a bearing shoe; a power actuated spud pivotally connected at its lower end to the central portion of the shoe; guides mounted on the car, one to each side of the power spud; a spud 85 passing downwardly through each guide, said spuds each being produced from a series of spaced bars; a pivotal connection between the lower end of each of said spuds and the adjacent end of the shoe; a series of friction 90 plates mounted within each guide and between which the bars of the spud extend; a pressure plate mounted in the outer part of each guide; a screw for forcing each plate inwardly; and a hand lever for actuating each 100 screw.

In testimony whereof I have signed my name to this specification.

HENRY H. TALBOYS.
